UNITED STATES PATENT OFFICE.

FRANKLIN A. WELLER, OF PHILMONT, NEW YORK.

APPARATUS FOR DYEING OR BLEACHING.

SPECIFICATION forming part of Letters Patent No. 735,183, dated August 4, 1903.

Application filed October 19, 1899. Serial No. 734,071. (No model.)

To all whom it may concern:

Be it known that I, FRANKLIN A. WELLER, a citizen of the United States, and a resident of Philmont, in the county of Columbia and State of New York, have invented certain new and useful Improvements in Skein Dyeing and Bleaching Apparatus, of which the following is a specification.

My invention relates to apparatus upon which skeins of yarn may be mounted and by which the yarn will be dipped into a vat or tank for dyeing, bleaching, or the like.

The objects of my invention are to provide an apparatus upon which the skeins of yarn may be conveniently mounted, carried into, and removed from the vat and reversed in position end for end at the bottom and top of the carrier with a minimum expenditure of time and by which the skeins will be held in suitable position to insure proper dipping and trailing in the vat and be automatically shifted on the skein-sticks in a manner to insure access of the liquid uniformly to all parts of the material.

To these ends my invention consists in a suitable carrier upon which skein-sticks may be mounted at suitable points, said carrier being preferably in the form of two parallel endless chains provided with adjustable clips for supporting the skein-sticks, guides within and outside of the vat under and over which, respectively, the carrier passes, and preferably consisting of sprocket-wheels mounted upon a common axle and upon which the chains travel, and a drag bar or bars or retarding device over which the skeins of yarn drag during their circuit for the purpose of shifting and turning them upon the skein-sticks, said drag-bars preferably consisting of sleeves surrounding the axles of the sprockets, so that the shifting and turning of the yarn occur at the points where the carrier passes its guides.

My invention further consists in the particular construction of the clips for holding the skein-sticks, each of which comprises a U-shaped bracket formed on one side with a diagonal slot providing a bearing for a skein-stick trunnion formed in the outer ends of its arms with seats or recesses to receive the edges of the chain-links and adjustably clamped upon the latter by means of a screw

extending between its arms and a spring-keeper mounted upon the clamping-screw as a pintle and held against the trunnion of the skein-stick when in the bearing through the medium of a spring.

My invention further consists in providing the skein-sticks with deflecting-guards at their ends, extending from the flanges diagonally inward in a manner to prevent the yarn riding up to the flanges and becoming entangled therewith or getting beyond the same.

My invention will be fully understood upon reference to the accompanying drawings, in which—

Figure 1 is a sectional end elevation of a vat or tank to which my invention is applied. Fig. 2 is a detail perspective, on an enlarged scale, showing a portion of one of the chains with the adjustable clips mounted thereon. Fig. 3 is an elevation in a plane at right angles to Fig. 1, showing a plurality of apparatus applied to a vat to illustrate the position of the skeins upon the carrier and the passage of one of the skeins over a drag-bar or retarding device. Fig. 4 is an enlarged detail view of one end of a skein-stick constructed in accordance with my invention, together with the supporting-clips on the chain, the clip being shown in vertical section. Figs. 5, 6, 7, and 8 are sectional views representing various forms of skein-sticks.

1 represents a vat or tank, and 2 a carrier in the form of parallel endless chains passing around upper and lower guides, of which the lower comprises sprockets 3, mounted upon an axle 4 in bearings 5 within the vat 1, while the upper guide comprises sprockets 6 upon an axle 7, mounted in suitable shaft-hangers 8. The lower bearings 5 are preferably made vertically adjustable in the vat through the medium of screws 9, threaded in brackets 10 and fixed by jam-nuts 11.

12 represents clips mounted at suitable points upon the parallel chains 2 to provide bearings for the trunnions of skein-sticks 13, upon which are mounted any suitable number of skeins A.

14 represents drag-bars or retarding devices located in the path of the skeins in position to exert a dragging or turning effect upon the skeins as they pass. Said drag-bars are preferably located at the turning-point

in the travel of the carrier, and preferably comprise sleeves surrounding the axles 4 and 7 of the sprockets 3 and 6. These drag-bars perform a most important function in the 5 operation of my apparatus in that they cause a shifting and a twisting or turning of the skeins upon the skein-sticks, the importance of which is well understood in the art. This result has generally heretofore been accomplished by the use of special mechanism for 10 engaging the flanges or other parts of the skein-sticks at some point or points in their travel. I find in practice, however, that this result is fully accomplished by having the 15 skeins pass over the drag bars or sleeves 14 in the manner suggested in Fig. 3. As this action takes place the inner side of the skein strikes the sleeve first and is tightened, while the outer side momentarily remains slack. 20 The result is that there is a slight advancement of the skein in the nature of an endless-belt travel upon the skein-sticks, which action is followed by the contact or stretching of the outer side over the drag-bar, and one 25 side of the skein is caused to roll slightly upon the other and the strands are spread out, so that the whole effect of the drag-bar upon the skein is not only a longitudinal shifting, but a turning or twisting. This action 30 being repeated each time the skein goes around the drag bar or sleeve causes the strands of the skein to be effectually shifted to the fullest desired extent, and I am thus enabled by a most simple mechanism to accomplish 35 that which has heretofore been accomplished only by the use of complicated mechanism.

The shape of the skein-sticks is not material and may be varied at will. Several suggested shapes are illustrated in Figs. 5, 6, 7, 40 and 8.

The apparatus illustrated in Fig. 1 may be arranged in any desired number, as suggested in Fig. 3 the number being limited only by 45 the length of the vat, as will be readily understood. The shafts 4, with their sprockets 3, act as idlers, motion being preferably imparted through the shafts 7, which are driven through the medium of a clutch 15, controlled 50 by shipping-levers 16, fulcrumed at 17 from a main shaft 18, running transversely to the ends of the shaft 7 and imparting rotation to the latter through small gear-wheels 19 and large gear-wheels 20.

55 The construction of the adjustable clips 12 will be understood from Fig. 2, in which it will appear that each comprises a U-shaped bracket 22, provided in one of its arms with a diagonal bearing-slot 23 and [on the inner 60 faces of the outer ends of its arms with recesses or seats 24 for the rounded sides of the links 21 of the carrier 2. The clips are clamped to the links 21 through the medium of screw 25, headed in one of the arms and 65 threaded in the other. From the construction of the parts it is obviously an easy mat-

ter to loosen the screw 25 slightly and to shift a clip 12 up or down on the chain at will. 26 represents a keeper pivoted upon the screw 25 through the medium of its bearing 27 and 70 forced in a direction to hold the trunnion in the slot 23 by means of a spring 28, one end of which engages the keeper at 29, while the other engages beneath a fixed part of the clip, as shown at 30. The end of the keeper 75 26 protrudes beyond the clip, so that the trunnion may be readily inserted by forcing it up beneath the keeper and then into the slot. It is to be understood that the clips are made in pairs—that is to say, with their bearing-slots on opposite sides—so that when a pair of clips is placed upon the parallel chains their bearings will be opposed and for the further purpose of admitting the clips to be arranged in sets of four, with the diagonal 80 slots of the clips mounted upon the same chain extending in opposite directions. This will be understood upon reference to Fig. 2, from which it will also be seen that the weight of the skein will hold the upper skein-stick 90 trunnion in the diagonal slots by gravity, while the trunnions of the lower skein-sticks, which bear no weight, will be held in place by the keepers 26. It thus becomes practicable to adjust the clips and space the sticks 95 apart, so as to allow slack in the skeins and permit them to make the turns around the drag-bars 14. This relation between the clips continues after the chains round the upper guide and travel downward, for the 100 parts are then completely reversed and the lower clips on the upward movement now become the upper clips on the downward movement and support the skeins, and their diagonal slots are in position to support the skein- 105 sticks by gravity.

It is desirable in the treatment of skeins as above described to provide some means for preventing the strands riding up to and over the flanges 31 of the skein-sticks 13. To 110 insure against this, I employ diagonal guards 32, which extend from the flanges inward at an angle which will prevent the skeins riding up and which will keep the skeins at an ample distance from the flanges to prevent interference. 115

In practice all of the working parts of my apparatus are preferably made of bronze or other metal non-corrosive in the chemicals through which they pass. 120

Having thus described my invention, the following is what I claim as new therein and desire to secure by Letters Patent:

1. A yarn-dipping apparatus comprising a vat, an endless carrier having trunnionbearings, skein-sticks trunnioned in the said trunnion-bearings and adapted to carry skeins of yarn by both ends thereof, guides around which the carrier passes, and drag-bars mounted coaxially with said guides and whereby 125 the skeins of yarn are shifted and their skein-sticks caused to turn with the ends of the 130

skeins on their trunnion-bearings; substantially as described.

2. In a dipping apparatus, the combination of a vat, a pair of sprocket-wheels mounted upon a common axle within the vat, a pair of sprocket-wheels mounted upon a common axle outside the vat, endless chains passing around the corresponding sprockets of the respective pairs, clips fixed upon the chains at corresponding points and providing thereon opposite trunnion-bearings for skein-sticks, and sleeves surrounding the axles between the sprocket-wheels and providing drag-bars for the skeins at the turning-points in the travel of the chains; substantially as and for the purposes set forth.

3. In an apparatus of the character set forth, a skein-stick clip or support constructed with a trunnion-bearing, clamping-arms, and a screw for drawing said arms together upon the skein-carrier; substantially as set forth.

4. In an apparatus of the character specified, a skein-stick clip for adjustable attachment to an endless chain, constructed of a U-shaped bracket provided with seats on the opposite faces of its outer ends, and with a trunnion-bearing in one of its arms, and a clamping-screw extending between said arms and drawing them inward; substantially as set forth.

5. In a skein-stick clip for yarn-dipping apparatus, the combination of the U-shaped frame provided with a bearing in one of its arms, the clamping-screw, and the spring-keeper mounted upon the clamping-screw

and overlapping the trunnion when in the bearings; substantially as set forth.

6. In a skein-dipping apparatus, a skein-stick provided with end flanges and inwardly inclined guards extending from the outer portions of the flanges to the sticks at an angle that prevents the strands of the skein riding up on them to the flange; substantially as set forth. 40

7. In an apparatus such as described, the combination with a vat or tank, an overhead shaft, sprocket-wheels carrying sprocket-chains traveling over said wheels and into the vat or tank, and yarn-sticks supported by said chains; of a drag-bar or retarding device lying in the path of the yarn mounted on said sticks, and with which said yarn contacts to change the position of the yarn with relation to the sticks. 50

8. In an apparatus such as described, the combination with a tank, the overhead shaft, sprocket-wheels, carrying chains passing over said sprocket-wheels and into the tank, and yarn-sticks mounted on said chains; of a sleeve on a shaft intermediate the sprocket-wheels, with which the yarn on the sticks contacts to retard one side of the yarn and change its position with relation to the sticks. 60

Signed at Washington, District of Columbia, this 19th day of October, 1899.
